UNITED STATES PATENT OFFICE.

JOSEPH L. JAFFE, OF CLEVELAND, OHIO.

LIGHTING FIXTURE.

Application filed July 10, 1923. Serial No. 650,628.

To all whom it may concern:

Be it known that I, JOSEPH L. JAFFE, a citizen of the United States, and a resident of Cleveland, county of Cuyahoga, and State 5 of Ohio, have invented a new and useful Improvement in Lighting Fixtures, of which the following is a specification, the principle of the invention being herein explained, and the best mode in which I have contemplated 10 applying that principle so as to distinguish it from other inventions.

The present improvements relating, as indicated, to lighting fixtures have more particular regard to the provision of a fixture for use with modern high powered incandescent lamp bulbs of the type now generally employed for interior illumination of stores, offices, schools, factories and the like. One object of the invention is to provide 20 an improved form of globe and holder therefor, the latter being adapted for use interchangeably either with a ceiling collar or suspended support. A further object is the provision of a reflector of improved construction that will utilize the upward rays ordinarily lost through absorption in this type of fixture. Still another object is the provision of means for ventilating not only the fixture as a whole, but also such reflector 30 so as to prevent tarnishing or peeling of the latter under conditions of actual use.

To the accomplishment of the foregoing and related ends, the invention, then, consists of the means hereinafter fully described and particularly pointed out in the claims, the annexed drawing and the following description setting forth in detail certain mechanism embodying the invention, such disclosed means constituting, however, 40 but one of various mechanical forms in which the principle of the invention may be used.

In said annexed drawing:—

Fig. 1 is partly a side elevation and partly 45 a central vertical section of a fixture embodying my present improvements, such fixture being carried from a suspended support; Fig. 2 is a similar view showing the upper portion of the fixture where arranged 50 to be secured to a ceiling collar; Fig. 3 is a broken bottom plan view of the reflector that constitutes a feature of such lighting fixture; and Figs. 4 and 5 illustrate details 55 of construction.

The high powered incandescent lamp 1 is

mounted in a downwardly directed receptacle or socket 2 of familiar type in the case of both forms of construction thus shown in Figs. 1 and 2. The only difference between the two forms of construction in question lies in the manner in which such socket is secured, i. e. in the one case to a pendent support 3 (Fig. 1), and in the other to a spider or ring 4 that is adapted to be attached to the ceiling in the usual way (Fig. 60 65 2). In the case of such pendent support an enclosing shell 5 of suitable form is provided which encloses the support 3 and the upper portion of the socket 2, such shell having a depending flange through which 70 project inwardly a series of set screws 6. While a shell 7 of somewhat different contour similarly encloses the mounting for the socket 2 in the case of the second construction, it likewise terminates in a downwardly 75 directed flange provided with similar set screws 6.

The function of such set screws 6 is to engage with an upwardly projecting collar 8 of the holder 9 which is identical in both 80 85 constructions, i. e. capable of use interchangeably with either of the supports just described. In order to insure uniform spacing all around, I may employ spacing bushings 6^a in connection with such screws, as shown in detail in Fig. 4.

It will be noted that the diameter of the collar 8 is smaller than that of the downwardly depending flanges of shells 5 and 7 so that when the holder is secured in place 90 by means of the screws 6, an annular space is left all around, thus permitting ventilation of the interior of the holder and globe 10 which is in turn attached to such holder by means of a series of set screws 11 in the 95 lower depending flange 12 of the holder. Secured permanently to the holder, so as to lie in spaced relation inwardly of such flange 12, is a series of spring clips 13, shown in detail in Fig. 5. The distance between 100 the clips and flange is sufficient to permit of the ready insertion of the outwardly curved or beaded upper edge of the shade or globe 10, as clearly shown in Figs. 1 and 2, such edge forming a more or less tight closure with the intermediate portion of the holder.

Each clip 13 is formed with a circumferential, inwardly directed channel or groove 14 which is adapted to engage with 110

the periphery of the annular reflector 15, the detail construction of which will perhaps be best understood upon reference to Fig. 3. Such reflector, in other words, 5 comprises a sheet metal back 16 in the form of a plate of general annular shape. The outer edge of such plate is curved inwardly to provide a flange 17 behind which the outer edges of the segmental glass reflector parts 10 18 are adapted to be inserted and thus held in place, the inner ends of such reflector parts being then secured by means of hook-like projections 19 stamped out of the metal composing the back 16 and adapted to be 15 bent under such reflector parts when they are assembled on the back. Another transversely disposed hook 19^a projects between two adjacent reflector parts and serves as a stop to prevent sliding movement of all such 20 parts around the back in which they are thus held. Damage to the silvering is in this way prevented. The segmental glass plates 18, which compose the reflector proper, are strictly plane so that the reflector surface 25 provided is likewise plane throughout its entire annular extent. However, the back 16 in transverse cross-section is raised above the plane which the segmental glass plates 18 thus occupy so as to provide an air space 30 on the silvered sides of such plates. In addition such back is provided at intervals with apertures 20 whereby complete ventilation of the space thus provided between the glass reflector plates and the back is assured.

The contour of the globe or bowl 10 is such that the rays of light as reflected from the surface of the glass reflector plates 18 will be diffused rather than concentrated. 40 The material of the globe or bowl may also be selected to produce an additional diffused effect and to modify the tone of the light that is transmitted therethrough, but by reason of the shape and disposition of the reflector 15 a minimum amount of light will be lost through absorption within the fixture. It will be noted that while an annular clearance space is left between the outer edge of the reflector back 16 and the 45 upper edge or lip of the bowl, so that air may circulate freely between the globe and holder and escape from or enter the latter through the annular space previously referred to as being provided between the collar 8 of such holder and the downwardly depending flange of shell 5 or 7, the central opening in the reflector back 16 fits snugly around the stem of the light bulb 1, only sufficient clearance being left at this point 50 to take care of the slight variations that occur in the diameter of such stem. Furthermore, the use of highly efficient silvered glass plates in the construction of the reflector 15 is rendered possible by the form of the

back 16 and the provision of the ventilating openings 20 in such back, whereby overheating and consequent blistering of the silvering on the plates is avoided.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a lighting fixture, the combination with a suitable support including a lamp socket and a shell enclosing same, of a globe holder secured to said shell, a series of downwardly directed clips on said holder, and an annular reflector peripherally attached to such clips, said reflector comprising an annular plate having its outer edge recurved inwardly, a series of segmental glass reflector parts having their outer ends inserted behind such recurved edge, and hook-like projections adjacent the inner edge of said plate engaging the inner ends of said reflector parts.

2. In a lighting fixture, the combination with a suitable support including a lamp socket and a shell enclosing same, of a globe holder secured to said shell, a series of downwardly directed clips on said holder, and an annular reflector peripherally attached to said clips, said reflector comprising an annular plate having its outer edge recurved inwardly, a series of segmental glass reflector parts having their outer ends inserted behind such recurved edge, and hook-like projections adjacent the inner edge of said plate engaging the inner ends of said reflector parts, the portion of said plate between its edges being raised above the plane of said reflector parts to provide a ventilating space.

3. In a lighting fixture, the combination with a suitable support including a lamp socket and a shell enclosing same, of a globe holder secured to said shell, a series of downwardly directed clips on said holder, and an annular reflector peripherally attached to said clips, said reflector comprising an annular plate having its outer edge recurved inwardly, a series of segmental glass reflector parts having their outer ends inserted behind such recurved edge, and hook-like projections adjacent the inner edge of said plate engaging the inner ends of said reflector parts, the portion of said plate between its edges being raised above the plane of said reflector parts to provide a ventilating space and apertures being formed in such raised plate-portion.

Signed by me, this 9th day of July, 1923.
JOSEPH L. JAFFE,
